CLAIM

The ornamental design for a key telephone set, substantially as shown and described.

DESCRIPTION

FIG. 1 is a perspective view of a key telephone set showing my new design;

FIG. 2 is a plan view thereof;

FIG. 3 is a front view thereof;

FIG. 4 is a right side view thereof;

FIG. 5 is a rear view thereof;

FIG. 6 is a left side view thereof; and

FIG. 7 is also a perspective view thereof with its handset removed from the cradle in the stand and inverted and spaced to one side to show the underside of the handset and the cradle surfaces.

The showing of a cord in abbreviated and fragmentary form is for convenience of illustration.

FIG. 1

FIG. 2

FIG. 5

FIG. 6

FIG. 7
